METHOD OF AND APPARATUS FOR FILLING
AND PACKING CONTAINERS

Francis B. Fishburne, Asheville, N. C., Clarence H. Hinnant, Jr., Richmond, Va., and Thomas A. Ricks, Durham, N. C.

Application March 1, 1949, Serial No. 79,094

12 Claims. (Cl. 226—71)

1

This invention relates to filling and packing containers with loose material, and more particularly to filling and packing hogsheads with tobacco.

It is common practice to pack tobacco in hogsheads either in the form of whole leaves, or in the form of "strips," that is to say, leaves from which the central stems have been removed or partially removed.

The usual method is to deliver the tobacco into the top of the hogshead, either in batches, or, in the case of strip tobacco, in a continuous stream as the material is produced. When the hogshead is sufficiently full, the delivery is stopped, or diverted, and the contents are distributed by laborers "walking" it into place, or by other means. The contents are then pressed or tamped down by means of a suitable power press. This filling and pressing operation may be repeated several times, before the desired quantity of tobacco has been packed into the hogshead.

This method of packing, as heretofore practiced, has resulted in the mass of tobacco being packed more tightly in the middle than at the sides, thus producing a hard central core.

This has created a serious problem. When the packed tobacco is delivered to processors or manufacturers, the mass is removed from the hogshead and is then usually subjected to the action of steam, heat, hot air or vacuum processing to properly condition the tobacco for further operations. It has been found however that this conditioning treatment does not readily penetrate or extend into the hard central core, and thus it has been impossible to produce uniform results throughout the mass of tobacco.

The main object of the present invention is to overcome this difficulty, and to this end the invention contemplates a method of and means for so filling and packing a hogshead that the central portion shall not only be no denser than the side portions, but shall even be less dense, or looser. This is accomplished by delivering the tobacco into the hogshead from a chute or spout and causing relative rotation between the hogshead and chute so that the tobacco is laid in the hogshead in an annular zone.

Another object of the invention is to devise improved means whereby the successive filling and tamping of the hogsheads is facilitated, such means including a movable support on which the hogshead is carried and by which it may be readily shifted back and forth from a posi-

2

tion under the delivery spout or chute, to a position beneath a suitable tamping press.

A still further object is to provide a plurality of filling stations with means for feeding the material to either one or the other as desired, whereby one hogshead may be filled while another is being tamped.

In order that the invention may be readily understood, reference is had to the accompanying drawings forming part of this specification and in which:

Fig. 1 is a diagrammatic view, partly in side elevation and partly in section, illustrating one form of the invention, this form comprising means for rotating the hogshead as the material is delivered thereto.

Fig. 2 is a plan view of the arrangement shown in Fig. 1.

Fig. 3 is a view similar to Fig. 2 but showing a somewhat modified construction.

Fig. 4 is a side elevation illustrating another form of the invention, namely a form in which the hogshead remains stationary while the delivery spout rotates or gyrates about the axis of the hogshead.

Fig. 5 is a vertical sectional view on an enlarged scale through the delivery spout and associated mechanism shown in Fig. 4, parts being broken away.

Fig. 6 is a plan view of the arrangement shown in Fig. 4, parts being omitted.

Fig. 7 is a horizontal section substantially on the line 7—7 of Fig. 4.

Fig. 8 is a schematic plan view showing our improved means for filling and tamping the hogshead, and

Fig. 9 is a similar view, in fragmentary side elevation, illustrating a filling station and the tamping press, parts broken away.

Referring to the drawings in detail, and more particularly first to Figs. 1 to 3 thereof, 1 designates a conventional hogshead having a bottom head 2, and this is supported on a platform 3 mounted at the upper end of a rotary shaft 5 driven in any suitable way. The platform 3 has an extension 4 which fits up inside the lower end of the hogshead to hold it in position.

As is customary in apparatus for filling hogsheads with tobacco, we provide at the top of the hogshead 1 a "false hogshead" or charger 6, and a feed chute 9 is arranged to deliver tangentially into the top of this charger. Preferably the chute has an arcuate edge 9a conforming with the curvature of the charger.

With the arrangement so far described, it will

be seen that as the hogshead and charger are rotated by the shaft 5 on a vertical axis and the tobacco is fed continuously from the chute 9, it will be delivered in a more or less annular zone adjacent the side walls of the hogshead. In other words more material will be delivered in the zone next to the side walls than will be delivered in the central region of the hogshead. Thus after the hogshead is filled and the tobacco pressed down, the central portion of the mass will be more loosely packed than the outer portions thereof, thus providing what may be called a "hollow core."

In Fig. 1 we have conventionally illustrated a plunger or piston 7 carried at the lower end of a piston rod 8 operating in a hydraulic cylinder (not shown) for tamping or pressing the tobacco.

In order to still further assure the delivery of the tobacco in an annular zone we may employ, if desired, a curved guide or baffle 10 supported above and concentrically with the hogshead by the plunger 7. This guide or baffle is of flexible material such as canvas and preferably carries a heavy ring 11 at its lower end to maintain it in shape. As seen in Fig. 2, this guide or baffle 10 defines an annular space between itself and the walls of the charger, in which space the tobacco delivered by the chute 9 is more or less confined.

It will be understood that the canvas guide or baffle 10 depends from the plunger 7 and hangs down into the upper end of the charger a suitable distance which may be regulated by setting the plunger 7 at the desired point.

When the plunger descends to press the tobacco in the hogshead, as indicated in dotted lines in Fig. 1, this canvas guide is compressed between the plunger and mass of tobacco, and collapses longitudinally.

Instead of a complete circular guide or baffle such as shown in Figs. 1 and 2 we may employ only an arcuate segmental baffle as shown at 10' and 11' in Fig. 3, this segmental baffle being disposed at a point adjacent the end of the feed chute 9.

Instead of rotating the hogshead, we can produce substantially the same results by delivering the material into a stationary hogshead by means of a rotary or gyratory spout, mounted to revolve on the axis of the hogshead. Such an arrangement is shown in Figs. 4 to 7. In these figures we construct at an elevated point a suitable frame 12 on which is fixed a stationary supporting ring formed of a horizontal annular member 13 and a vertical cylindrical member or flange 14, secured together as by welding. A suitable hopper 15 is mounted on this ring.

Projecting downward beneath the ring is a rotary spout comprising a relatively short vertical portion 16 and a diagonally extending or inclined portion 17. This spout is rigidly secured at its upper end to a ring gear 18 which is supported on a series of rollers 19 journaled on pins 20 set into the cylindrical member 14.

Meshing with the ring gear 18 is a driving pinion 21 carried at the lower end of a shaft 21' which projects downwardly from a speed reducing gear box 22, to the upper end of which is connected a driving motor 23, all of these parts being supported on a suitable frame 24. A drip pan 24' is also carried by this frame and is positioned under the gear 21 so as to catch any oil which may drip from the gearing, and thus protect the tobacco from contamination.

A non-clog finger 17' is secured to the rotary spout and extends up into the bottom of the

hopper as clearly shown in Fig. 5. An endless belt 25 is arranged to deliver the tobacco into the hopper 15.

The hogshead 1 to be filled, surmounted by a suitable charger 6, is supported on a dolly 26 mounted on wheels 27 as clearly shown in Fig. 4, and in practice the hogshead and charger are positioned with their axes coinciding with the axis of rotation of the spout 16, 17. The motor 23 drives the ring gear 18 through the gear box 22 and pinion 21, thus causing the spout to rotate or gyrate about a vertical axis as indicated in Fig. 7. It will be seen that the tobacco discharged from the spout is directed against or toward the side walls of the hogshead and charger so that the tobacco is delivered largely in an annular zone adjacent such walls. Thus, as the tobacco builds up in the hogshead the mass is denser around the sides than at the center.

Where, in the appended claims, we use the word "container," we intend this term to include the combined hogshead and charger assembly, as shown in Figs. 1 and 4.

In Figs. 8 and 9 we have illustrated our improved arrangement for facilitating the filling and tamping of hogsheads by means of a rotary spout as above described.

In this improved arrangement two filling stations are provided having hoppers designated 15 and 15' in Fig. 8 and beneath these hoppers are placed the hogsheads and chargers to be filled as indicated in broken lines at 6' and 6'' respectively.

A horizontally disposed endless conveyer 25' extends between the two hoppers just above the same as shown. Means are provided for driving this conveyer in either direction desired as indicated by the arrows in Fig. 8 and a conveyer 28 is arranged to feed the tobacco onto the conveyer 25' at a point between the two hoppers. Thus the material fed onto the conveyer 25' may be delivered either into one hopper or the other, depending upon the direction in which it is driven.

Adjacent the two filling stations just described is set up a tamping press, preferably of the hydraulic type, and comprising a plunger 7 carried by a piston rod 8. This piston rod works through a guide or sleeve 29 carried between a pair of frame members 30 which are in turn supported at their ends by a pair of posts or columns 31, secured to the frame members as by welding.

From the foregoing it will be understood that in practice the hogsheads to be filled are each mounted upon a movable support such as the dolly 26, shown in Fig. 4, so that they can be readily moved into position beneath the hoppers at the filling stations. When the hogshead 6' for example is filled to the desired extent with loose tobacco it is shifted to a position beneath the plunger of the tamping press, as indicated at the lefthand side of Figs. 8 and 9, so that the loose tobacco may be pressed down or tamped. While this tamping operation is in progress the conveyer 25' is reversed so as to deliver the tobacco into the hogshead 6''. Then the first hogshead is removed from the press and shifted back into position under the hopper 15, while the second hogshead 6'' is shifted into position under the press, the conveyer 25' being again reversed. Thus, by this arrangement, it will be seen that one hogshead is being filled while the other is being tamped, the hogsheads being alternately shifted back and forth between the respective hoppers and the tamping press several times during the filling operation.

What we claim is:

1. The method of filling a cylindrical container with loose fibrous material which comprises rotating such container in a vertical position about its own axis, delivering a stream of material tangentially into the upper end of the container at a point adjacent the wall thereof, so that such material is deposited mainly in an annular zone, stopping the delivery of material after the desired amount has accumulated, and exerting pressure downwardly on the accumulated mass to compress the same, whereby the material is packed less tightly at the center than at the sides.

2. The method of filling a cylindrical container with loose, fibrous material which comprises feeding a stream of material into said container from a chute disposed to deliver such material at a point adjacent the wall thereof, and producing relative rotation between said chute and container about the axis of the latter until a substantial mass of material has been deposited, stopping such rotation and delivery of material, and exerting pressure axially upon the deposited mass to compress the same, whereby the compressed mass is packed more tightly adjacent the sides than at the center.

3. The method of filling a cylindrical container with loose fibrous material which comprises rotating such container in a vertical position about its own axis, delivering a stream of material into the upper end of the container at a point spaced laterally from the center thereof, until a substantial mass of material has been built up in an annular zone, stopping the rotation of the container and feeding of material and exerting pressure downwardly on the accumulated mass to compress the same.

4. Apparatus for filling a cylindrical container comprising, in combination, means for supporting the container in upright position, a chute arranged to deliver material into the upper end of said container in such a manner that it is deposited chiefly at a point adjacent the wall thereof, means for producing relative rotation of said chute and container about the axis of the latter, whereby a mass of material is built up in an annular zone, and a power-operated press plunger, normally outside of the container while material is being delivered into the same, arranged to enter the container and exert axial pressure on the mass of material thus built up.

5. Apparatus for filling a cylindrical container, comprising, in combination, means for supporting the container in upright position, means for rotating the container about its own axis, a stationary arcuate form disposed concentrically within the upper end of the container and defining with the walls thereof an annular space, and means for delivering a stream of material into such annular space.

6. Apparatus for filling a rigid cylindrical container, comprising, in combination, means for supporting the container in upright position, means for rotating the container about its own axis, a generally vertically disposed stationary arcuate form of smaller radius than the container suspended above the container and extending concentrically down into the upper end thereof, thus forming with the walls of the container a space which is at least partially annular, and means for delivering a stream of material into such space.

7. Apparatus for filling a rigid cylindrical container, comprising, in combination, means for supporting the container in upright position,

means for rotating the container about its own axis, a generally vertically disposed stationary arcuate guide of smaller radius than the container suspended above the container concentrically therewith, means for adjusting said guide vertically so as to cause it to project down into the container to a varying extent, said guide forming with the walls of the container a space which is at least partially annular, and means for feeding a stream of material into such space.

8. Apparatus for filling a cylindrical container with compressible material and for compressing the same, comprising, in combination, means for supporting the container in upright position, means for rotating the same about its own axis, a reciprocable press plunger disposed above said container, an arcuate guide of smaller radius than the container suspended from said plunger concentrically with said container and defining with the wall thereof a space which is at least partially annular, and means for feeding a stream of material into such space, said arcuate guide being flexible, whereby it may collapse longitudinally when said plunger is lowered upon the mass of material in the container to compress the same.

9. Apparatus for filling a cylindrical container with compressible material and for compressing the same, comprising, in combination, means for supporting the container in upright position, means for rotating the same about its own axis, a reciprocable press plunger disposed above said container, an arcuate guide of smaller radius than the container suspended from said plunger concentrically with said container and defining with the wall thereof a space which is at least partially annular, and means for feeding a stream of material into such space, said arcuate guide being formed of flexible sheet material having a rigid, heavy element at its lower end serving to keep the flexible material extended, said guide being constructed to collapse longitudinally when compressed between the mass of material in the container and the said plunger during the down stroke of the latter.

10. Apparatus for filling a cylindrical container, comprising, in combination, means for supporting the container in upright position, a chute for delivering a stream of material into said container, means for producing relative rotation of said chute and container about the axis of the latter, and a circular form of smaller diameter than the container supported independently of the container adjacent the upper end thereof during the filling operation, said form being disposed below said chute and concentric with said container and of such size as to provide an annular space between itself and the container walls, through which annular space the material is delivered from said chute.

11. Apparatus for filling a cylindrical container, comprising, in combination, means for supporting the container in upright position, a chute for delivering a stream of material into said container, means for producing relative rotation of said chute and container about the axis of the latter, and a circular form of smaller diameter than the container, means for so supporting said form that it may either be positioned adjacent the upper end of said container or lowered vertically into the interior thereof, said form being disposed, during the filling operation, adjacent the upper end of the container concentric therewith and below said chute, so as to provide an annular space between itself and the con-

tainer walls, through which annular space the material is delivered from said chute.

12. Apparatus for filling a cylindrical container, comprising, in combination, means for supporting the container in upright position, a chute for delivering a stream of material into said container at a point adjacent the wall thereof, means for producing relative rotation of said chute and container about the axis of the latter, whereby the material is deposited in an annular zone, around the sides of the container, and a press plunger mounted co-axially with said container and arranged to enter the same from above to compress the material deposited therein.
